UNITED STATES PATENT OFFICE.

KINSEY CADWALADER, OF ARGENTINE, KANSAS, ASSIGNOR OF ONE-HALF TO ROY L. HUTTON, OF KANSAS CITY, MISSOURI.

WAREHOUSE DUMPING TRUCK.

1,410,991.

Specification of Letters Patent. Patented Mar. 28, 1922.

Application filed February 5, 1921. Serial No. 442,787.

To all whom it may concern:

Be it known that I, KINSEY CADWALADER, a citizen of the United States, residing at Argentine, in the county of Wyandotte and State of Kansas, have invented certain new and useful Improvements in Warehouse Dumping Trucks; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to barrel trucks and it is particularly adapted for use in handling open head barrels with ease and dispatch.

While the invention is adapted to handle barrels and casks of various form and size, it is primarily intended for use in connection with open ended barrels in lubricating plants where the open ended barrel must be raised and transported to another place.

The specific embodiment of my invention selected for the purpose of illustration shows a novel means for clamping the barrel in the middle so as to balance the same in turning for the discharge, and I have shown the clamps laterally adjustable for different sized barrels, which are adapted to engage the barrel and lift it from its support.

I have also shown means for supporting the barrel upon a circular frame with handles provided with break joints whereby the handles may be used for propelling the vehicle or for turning it, as the occasion may demand.

While I have shown with considerable particularity the preferred form of my invention and will describe in detail the manner of construction in operating it, I do not wish to be understood as limiting myself to the particular form shown, but I reserve the right to make such changes in form, proportion and minor details in construction as come within the scope of the following claims and without departing from the spirit of my invention.

In the drawings,

Fig. 1 is a perspective view of a truck constructed in accordance with my invention.

Fig. 2 is a detail, perspective view of the clamp-operating slide.

Fig. 3 is a cross sectional view on the line 3—3 of Fig. 6.

Fig. 4 is a side elevational view of the truck.

Fig. 5 is a detail view of the slide operating mechanism and handle connection.

Fig. 6 is a sectional view on the line 6—6 of Fig. 3.

Referring now to the drawings by numerals of reference.

1 designates a semi-circular angle frame on which are suitable wheels or casters 2 and 3, there being standards or legs 4 fastened to the flange of the angle, as best seen in Fig. 1, so that the frame may stand in a horizontal plane when at rest. Upon the semi-circular frame 1 and near the respective ends thereof are standards 5 and 6 which are connected at their upper ends by a cross bar 7 and on these standards are sleeved 75 castings 8 and 9, each of which is provided with guide grooves or recesses 10 and 11 to receive the arms 12 and 13 of the horizontal slidable clamp-actuating yoke 14, to which is pivoted a connecting member 15, carrying 80 a clamp connection 16 for one of the clamps 17 or 18, the connections being such that the clamps may swivel upon the connection 16 and pivot in a horizontal plane by the clamp connection 15 so that the clamps are readily 85 adjustable to the barrel whereby the barrel is always supported in a vertical position.

The rear ends 19 and 20 of the clamps are connected by a coil spring 21, whereby the forward ends will have a tendency to move 90 apart. The inner edges of the arms 12 and 13 are toothed or serrated as at 22 and 23 to receive the teeth 24 and 25 of the curved clamp actuator 26, which is provided on its back with a dovetail 27 to engage a corresponding groove 28 in the sleeve 8, the curved portion 29 being adapted to ride in the spaces between the teeth and force the yokes forward so as to cause the clamps to bind against the cask or barrel.

The lower ends of the member 26 are provided with perforate lugs or projections 30, to be engaged by the end 31 of the lever 32, which is pivoted at 33 to the link 34, in turn supported on a bracket 35 carried by the 105 flange of the angle frame 1. The upper end of the lever 32 is provided with a slot 36 to be engaged by a bolt 37 in a guide 38 carried

by the handle lever 39, pivoted at 33 to the link 34. Therefore, if the bolt is withdrawn from engagement with the slot 36 through the medium of the connection 40 and the manually-operated device 41, the handle may swing down, as shown in Fig. 1.

There are two levers corresponding to 39, the opposite one being designated 39', and these levers are connected by a cross handle 42, the construction of the lever 39' being substantially that of the one designated 39, which is the only one shown in detail.

Carried by the respective arms 39 and 39' are pivoted racks or serrated latches 43 and 44, which are adapted to engage the edges of the keeper loops 45 and 46, carried by the flange of the angle frame 1 so that the sleeve members 8 and 9 may be held in any vertically adjusted position. For example, suppose the cask or barrel 47 is to be transported by the truck. The truck will be moved into position, as shown in Fig. 1, so that the clamps 17 and 18 and the sleeves 8 and 9 will be in their lowermost positions. The operator then moves the handle consisting of the members 39, 39', and 42 into the position shown in Fig. 4 and pulls down upon the bar 42 until the latch levers 43 and 44 engage the keepers 45 and 46, raising the member 26 to force the clamps into engagement with the barrel and raising the barrel off the ground. The bar 42 may then be tilted slightly upward, raising the standards 4 so that the truck may be rolled over the surface which supports it, the barrel being held off the ground because the latches 43 and 44 are still in engagement with their keeper loops. When the barrel is to be released, the bolts 37 may be withdrawn from the slots or notches 36 so that the clamps will automatically release themselves.

What I claim and desire to secure by Letters-Patent is:

1. In a device of the class described, a frame, barrel clamping means, a pivoted lever carried by the frame, a connection between the pivoted lever and the barrel clamping means whereby a swinging movement of the lever will effect a vertical movement of the barrel clamping means and a lateral clamping movement thereof.

2. In a device of the class described, a frame, a vertically movable barrel clamping means carried by the frame, pivoted levers for effecting movement of the barrel clamping means, handle levers having swinging movement independent of the first named levers, and means for locking said two sets of levers together.

3. In a device of the class described, a frame, standards carried by the frame, sliding sleeve members on the standards, barrel clamps carried by the sleeve members, wedges slideable on said sleeve members for adjusting the barrel clamps and means for imparting movement to said wedges.

4. In a barrel truck, a frame, standards carried by the frame, sleeve members slideable on the standards, ratchet bars slideable in the sleeve members, barrel engaging plates carried by the ratchet bars, wedges slideable upon the sleeves for engaging the ratchet bars and means for imparting movement to the wedges to cause the ratchet bars to clamp the plates against the barrel.

5. In a barrel truck, a frame, standards carried by the frame, barrel clamps slideably carried by the standards and clamp actuating means to simultaneously clamp and lift the barrel for transport.

In testimony whereof I affix my signature.

KINSEY CADWALADER.
